UNITED STATES PATENT OFFICE.

HENRY N. ELLIS AND WILLIAM C. ELLIS, OF LONE WOLF, OKLAHOMA.

DIVISION-BLOCK FOR HAY-BALERS.

No. 895,081.

Specification of Letters Patent.

Patented Aug. 4, 1908.

Application filed November 9, 1907. Serial No. 401,501.

To all whom it may concern:

Be it known that we, HENRY N. ELLIS and WILLIAM C. ELLIS, citizens of the United States, residing at Lone Wolf, in the county of Kiowa and State of Oklahoma, have invented certain new and useful Improvements in Division-Blocks for Hay-Balers, of which the following is a specification.

The present invention relates to improvements in division blocks of that character which are placed in baling presses at intervals, for the purpose of separating the compressed hay into bales of suitable sizes.

The object of the invention is to provide a division block which is peculiarly designed so as to be constructed of sheet metal, the various parts serving to reinforce each other to produce a rigid structure which will withstand considerable more wear than the ordinary wooden block which is frequently mashed or split.

For a full understanding of the invention and the merits thereof and also to acquire a knowledge of the details of construction and of the means for effecting the result, reference is to be had to the following description and accompanying drawings, in which:

Figure 1 is a perspective view of the division block embodying the invention, one of the faces thereof being removed; Fig. 2 is a vertical sectional view through one of the division blocks; Fig. 3 is a horizontal view through the same; and, Fig. 4 is a detail view of one of the strips employed in closing the bottom of the division block.

Corresponding and like parts are referred to in the following description and indicated in all the views of the drawings by the same reference characters.

Referring to the drawing, the numerals 1 designate the two faces of the division block which are formed of pieces of sheet material and are crimped to provide the parallel grooves 2 through which the wire utilized in baling the hay is inserted. Attention is directed to the fact that the mouths of the grooves 2 are contracted and that the hay is thereby prevented from entering the grooves in such a manner as to interfere with the threading of the wire therethrough. These two faces 1 are connected by a plurality of spaced and parallel partitions 3, the longitudinal edges of which are secured to the faces 1 and are provided with the notches 4 receiving the crimped portions forming the grooves 2. The mouths of these notches 4

are contracted to conform to the grooves 2 and an interlocking connection is thereby produced between the partitions 3 and the faces 1. The top of the division block is closed by a metallic strip 5 provided with crimped portions 6 receiving the extremities of the partitions 3 and rigidly connected thereto by rivets or other suitable fastening members. In a somewhat similar manner, the bottom of the block is closed by a plurality of short strips 7 having the ends thereof deflected inwardly and riveted or otherwise rigidly connected to the partitions 3. If found desirable, as in the present instance, depressions 8 may be formed in the faces 1 near the upper end thereof for the purpose of permitting a secure hold to be obtained upon the division block by the fingers when handling the same. It may be mentioned that the grooves 2 are larger than can be made in a wooden block and that the mouth of the grooves through which the wire escapes is much smaller, this feature of the invention having the advantage of preventing the hay from entering the grooves and interfering with the instant threading of the wires through the same.

Having thus described the invention, what is claimed as new is:

1. A division block of the character described, comprising spaced plates having portions thereof crimped to form grooves, and a plurality of partitions connecting the spaced plates.

2. A division block of the character described, comprising spaced plates having portions thereof crimped to form grooves, and partitions connecting the plates and arranged transversely of the grooves, the said partitions having an interlocking connection with the crimped portions of the plates.

3. A division block of the character described, comprising spaced plates having portions thereof crimped to form grooves, a plurality of partitions connecting the spaced plates, and strips closing the ends of the block.

4. A division block of the character described, comprising spaced plates having portions thereof crimped to form grooves, the mouths of the grooves being contracted, and partitions connecting the spaced plates and arranged transversely of the crimped portions, said partitions being notched to receive the crimped portions and the mouths of the notches being contracted to produce

an interlocking connection between the partitions and the plates.

5. A division block of the character described comprising spaced plates having portions thereof crimped to form grooves and the mouths of the grooves being contracted, a plurality of partitions connecting the plates, the edges of the partitions being notched to receive the crimped portions of 10 the plates and the notches having the mouths thereof contracted to form an inter-

locking connection between the partitions and the plates, and strips secured to the extremities of the partitions and closing opposite ends of the block.

15

In testimony whereof we affix our signatures in presence of two witnesses.

HENRY N. ELLIS. [L. s.]
WILLIAM C. ELLIS. [L. s.]
